UNITED STATES PATENT OFFICE.

EUGENE C. F. ERNST, OF PITTSBURGH, PENNSYLVANIA.

WALL-PAPER MACHINE.

Application filed February 19, 1927. Serial No. 169,598.

My invention consists of an improvement in machines for trimming, pasting, cutting, and manipulating wall paper for application to walls, ceilings, etc.

It has in view to provide a simple and applicable machine, operable in connection with a suitable table, whereby commercial wall paper may be drawn off from the usual roll through pasting mechanism and between severing mechanism for separation of the usual marginal edges, in any desired length, ready for application to the surface to be covered.

The machine as a whole involves various features of detail construction, adjusting mechanism, etc., as shall be more fully hereinafter described.

Referring to the drawings, showing a preferred embodiment of the invention:

Fig. 1 is a perspective view, showing the machine mounted at one end of its co-operating table, and illustrating the operation of shearing off any excess width;

Fig. 2 is an enlarged cross sectional view on the line II—II of Fig. 1;

Fig. 3 is a perspective view of the paste reservoir, with a surrounding retaining section of paper, detached;

Fig. 4 is a view similar to Fig. 1, showing the strip of paper being drawn through the machine from the roll;

Fig. 5 is an enlarged section on the line V—V of Fig. 3, showing the supporting clamp for the paste reservoir;

Fig. 6 is a similar view on the line VI—VI of Fig. 3, showing one of the endmost paper clamps;

Fig. 7 is an enlarged view in side elevation of the machine and the receiving end of the table, showing the paper strip passing therethrough;

Fig. 8 is a plan view of Fig. 7, partly broken away;

Fig. 9 is a longitudinal sectional view on the line IX—IX of Fig. 8;

Fig. 10 is a partial similar view, showing the knife raised above the paper;

Fig. 11 is a cross sectional view on the broken line XI—XI of Fig. 8;

Fig. 12 is a detail plan view of one end of the slitting knife frame;

Fig. 13 is a face view of the same, showing the slitting knife extending into the annular slot of the paper supporting roller;

Fig. 14 is an end view of Fig. 13, showing

the slitting knife extending into the annular groove of the roller;

Fig. 15 is a horizontal section on the line XV—XV of Fig. 13;

Fig. 16 is a cross section through the slitting knife frame on the line XVI—XVI of Fig. 8, with the blade holding plate detached;

Fig. 17 is a perspective view, detached, of one end portion of the knife frame and the holding plate.

The mechanism as a whole comprises the pasting and slitting machine A, adapted to be mounted by a suitable supporting bracket at one end of the folding or manipulating and cutting table B. The latter forms the subject matter of a separate companion application filed Feb. 19, 1927, Serial No. 169,597.

It will be understood that, while the machine is designed for co-operation and mounting relation with such table, it is not necessarily confined thereto, but may be utilized in connection with any suitable support and any suitable adjacent table or surface.

The machine A, in its entirety, comprises a unit so constructed as to be partially taken apart and packed into compact shape for carrying within a suitable case by the user, as is also the table B, as described in said companion application.

The pasting machine is preferably constructed of sheet or plate metal portions, rollers, etc., of a suitable kind, as aluminum or an alloy thereof, or of any other suitable alloy metal, adapted to withstand the active action of water or the elements for consistent endurance under the conditions of use.

At each end I provide oppositely located end plates 2—2, provided with securing brackets 3 riveted or screwed to the end plates, for attachment to the supporting bottom or base 4, preferably removably mounted on brackets 5 extending outwardly from the framework of the table B.

Base 4, which may be a board of comparatively thin light wood, rests upon brackets 5, as in Figs. 4 and 5, such base being provided with removable clips 6 having slotted terminals 7 extending upwardly behind the heads of screws 8 for connection therewith. Base 4 is provided at each end with clearance openings 9 for downward movement therethrough of the severed edges of the paper at both sides, as it is drawn through the machine.

Brackets 3 of end plates 2 are secured by

their flat bases 10 and thumb screws 11, extending upwardly through transverse slots 12 in the brackets, providing for exact lateral adjustment and fixture of the machine A on the shelf 4. Bracket 10 is also preferably provided with an outwardly extending handle 13 by which the machine may be exactly shifted and secured with relation to clearance openings 9.

10 End plates 2 are provided with two main cross bars 14 or wood or other suitable material, to which they are fixedly secured, as by screws, providing a rigid bracing support for the machine A. Secured to the outermost 15 cross bar 14 by thumb screws 15 are the paper roll carrying brackets 16 having at their outer ends L-shaped slots 17 for reception and support of the rod or spindle 18, upon which the paper roll 19 is mounted, for 20 withdrawal through the machine.

Extending transversely across the middle portion of the frame and secured to end plates 2 by downwardly extending flanges 20 is the flat supporting base 21 for the paper 25 strip, preferably made of suitable sheet or plate metal of the kind described. Between the outer edge of such supporting platform 21 and roll 19 is a freely rotatable paper supporting roll 22 carried by its terminal stem 30 bearings 23 in downwardly inclined slots 24, as in Fig. 7.

Just beyond the inner edge of platform 21 is an additional supporting roller 25, of wood or other suitable material freely and rotatably mounted by terminal studs or screws 26 in the end plates 2 and with its periphery substantially on the same level as the upper surface of the platform. The first supporting roller 22, as shown, extends slightly above 35 the platform surface, so that when the paste reservoir is in position, as in Fig. 9, its end walls and the packing inserts thereof will deflect the paper downwardly at a slight angle as shown, insuring leakage-proof 40 contact. In advance of supporting roller 25 is an additional supporting roller 27, freely rotatable by its central end projecting stem 28 in slots 29 of plate 2.

Terminal collars 30 are secured on the 50 outer ends of stem 28 and secured thereto by set screws 31, maintaining the roller 27 in exact alinement and preventing lateral movement during its free rotation. At each end roller 27 is provided with an annular clearance slot 32 for reception of the edge slitting knife of the cutter mechanism, hereinafter described, for the purpose of severing the blank edges of the paper roll from its main middle portion.

55 Frame members 14 are connected at their ends by similar cross members 33, providing a stabilizing base framing, and upon such framework is secured by screws 34 a flanged upwardly extending thin tapered clearance 60 plate 35. Such clearance plate extends into

slot 32 so as to clear it of any accumulated cuttings or other waste material, maintaining the slot open at all times.

Intervening between rollers 25 and 27 is a comparatively small freely rotatable paper 70 supporting roller 36 mounted by its terminal studs 37 in slots 38 of the main frame, slots 29 and 38 thus providing for easy removal of rollers 27 and 36 upwardly when desired. 75

For the purpose of slitting the edge portions of the paper as it is drawn forwardly from roll 19, I provide a separable L-shaped cross bar 39, the vertical portion 40 of which extends at each end slightly beyond 80 the top, for insertion downwardly through vertical receiving slots 41 at the upper rear portion of each end plate 2. Terminal L-shaped lugs 42 are bent outwardly from such strip member and engage the outer faces of 85 the main plates 2, while the lower portion of the vertical member 40 also extends through said slots and is provided with transverse locking openings 43.

Rotatable locking dogs 44 are pivotally 90 mounted, at 45, to the outer side of each end plate adjacent to the slot mounting of bar 40, and are provided with the extended manipulating lugs 46, lugs 47 for partially covering slot 29 when the locking dogs are opened, 95 and the locking horn 48. Said locking horn lies annularly around the pivoting center 45, and is adapted to be thrust through the locking slot 43 at each end of the slitter bar frame, as in Fig. 7. In such position the slitting mechanism is firmly held in position for use. 100

Mounted on the inner side of the L-shaped bar 39—40, is a knife supporting bar 49, lying along the inner face of the main bar, having flanged supporting shoes 93, and capable of a limited range of longitudinal adjustment along bar 39—40. For such purpose the main bar is provided with a series of slots 50 through which extend the holding screws 51 110 of bar 49, and which are thus capable of being fixedly adjusted and located in slots 50 by thumb screws 52.

Cutter bar 49 extends out at right angles at each end, forming a terminal knife securing plate 53. A supplemental angle shaped plate 54 extends at right angles to the inner face of adjustable strip 49, and is secured against the inner face of the knife support 53, forming a companion piece therefor. Such plate 54 has an inclined edge 55, against which bears the upper edge of a comparatively thin knife blade 57. A supplemental clamping plate 58 lies over the inner face of blade 57, having a similar upper edge 56, and is clamped to the outer bracket member 53 by a screw stud 59 having a thumb screw 60. 120

125 By such construction it will be seen that the knife blade 57 is firmly clamped at each 130

end of the adjustable inner bar 49, so that the blades may be accurately and fixedly located with their inwardly inclined cutting edges extending into the clearance slots or grooves 32 of roller 27. By such construction and arrangement the blades effect a clean severing separation of the edge strips 61 from the main paper strip, as it is drawn through the machine.

Extending outwardly beyond the last or trimming roller 27, and on a general level therewith, is a horizontal supporting shelf 62, pivoted in the end plates 2, at 63, by its downwardly extending lugs 64, and adapted to be thrown upwardly on the pivots when not in use for packing, as indicated in dotted lines in Fig. 7.

Platform 62 is slotted at each end, as at 65, the metal being turned downwardly, providing a downward sloping shelf 66, for delivery thereover of the slotted edge 61 through openings 9 in shelf 4 to a waste-basket or the like. End brackets 67, secured to the inner edges of end plates 2, and a vertical supporting plate 68, brace and support the plates 62 when in horizontal position, as in Figs. 7 and 9. The main paper strip passes onwardly over the platform from the pasting and slitting machine, onto the table B to any extent desired.

For the purpose of applying paste to the pasting side of the paper as it is drawn from the roll, the full width of the strip passes underneath the pasting box or reservoir b, which is mounted between the end plates immediately above the first supporting platform 21 and rollers 22 and 25.

Such pasting box is removably mounted between the end plates, and comprises a longitudinal rectangular sheet metal paste holder, having end plates 69 and longitudinal front side walls 70 and similar rear side walls 71. As shown, these side walls extend downwardly and then inwardly by sloping intermediate sections 72—73, and then flare outwardly by terminal sections 74—75.

The end walls 69 are provided with transverse sealing strips 76 of sponge rubber or other suitable material, held tightly against the end walls 69 by supplemental inner holding plates 77 secured to the end walls, as in Fig. 11. Sealing strips 76 press downwardly along the outer edges of the paper strip a as it is drawn through the machine, effectually sealing the interior paste containing space of the reservoir against endwise leakage.

The front outwardly flaring wall 74 extends downwardly over roller 22 with just sufficient clearance for the incoming strip, so that paste leakage in the opposite direction is effectually prevented.

For the purpose of also sealing the other side of the paste holder, and also of wiping the strip a with just sufficient paste, avoiding any unnecessary surplus, I provide addi-

tional sealing strips 78 and 79, also of sponge rubber or the like.

Said strips are mounted in holding brackets 80 and 81 respectively and such brackets are adjustably mounted for accurate placement of the sealing strips with relation to the end closing walls of the box, and in proper relation to the strip a and its lower supporting platform and rollers. Such mounting is effected by holding screws 82 extending through vertical slots in the main walls and having thumb nuts 83, for such adjustment and positive holding, as will be readily understood.

By means of the strips 78, 79, assisted by the end strips 76, I provide a supplemental chamber adjacent the main paste holding chamber. Such chamber will always contain a limited surplus amount of paste, ensuring even pasting of the surface from the first strip to the last, thus providing just the right amount at all times without variation or waste. Such paste as may pass under the first wiper 78 when the reservoir is full tends to insure coverage of the strip beyond the first wiper as the main supply lessens, with final wiping by wiper 79.

The end plates 69 of the paste holding box or reservoir are provided with projecting headed studs 84 extending through L-shaped slots 85 in the end plates 2 for separable placement. Locking holders 86 are pivoted at 87 to the end plates 2 at each opposite side having slots 88 for engagement of studs 84, as in Fig. 7, and lifting flanges 89 for upward swinging, providing for removal of the paste box.

As thus constructed the paste box is capable of holding any desired quantity of paste, as say up to one-half of its depth, the paste being supplied to the pasting side of the strip as it is drawn through for the full length of the paper a of roller 19. When the strip has been drawn through almost to its end, the last portion is cut off in front of the paste box by shears or a knife, and the rear and front free edges of such remnant are then folded upwardly around each opposite side wall of the paste box and clamped thereon, as in Fig. 3, with the edges of the paper turned downwardly over inside the top.

For the purpose of firmly holding the remnant sealing strip in such position so that the box may be removed, I utilize endmost clamps 90 having an inner block member 91 and outer clamping flanges 92, adapted to tightly hold the end portions of the strip at each side to the sides 70, 71.

A middle clamp for lifting the box is composed of two side members 94 hinged together at 95, having lower block portions 96 and outer clamping terminals 97 turned inwardly at 98.

Such clamp may be freely opened by pressing downwardly on its middle for release, and when applied, as in Figs. 3 and 5, will firmly

hold the sealing paper against the sides of the box as it is lifted upwardly.

By such means the entire paste box and its contents may be lifted away without leakage and laid aside temporarily, providing for placement of an additional new paper roll and the drawing of its end portion sufficiently far toward the table B to insure operation, after the paste box is replaced.

10 Thereupon the strip *a* is drawn forwardly, the unpasted portion is cut off, whereupon the operation of drawing the paper out, with application of the paste, and removal of the side edges may be continued throughout any 15 desired length of section, dependent on the work being done.

Table B is provided at its inner edge with a terminal cutting edge 99, across which the surplus unpasted portion of the paper may 20 be cut and thrown away, after having been drawn forwardly underneath the paste box just sufficient to apply paste outwardly to or slightly beyond such cutting location.

Thereafter the paper is drawn out sectionally and manipulated upon the table in 25 the manner more fully described in the application thereon.

The construction and operation of the machine will be readily understood and appreciated from the foregoing description. It 30 provides for accurate adjustment and placement of the various working parts, insuring complete coverage of the surface with paste accurate slitting of the excess edges, and 35 ample provision against leakage, with facility and ease of operation, greatly contributing to a maximum output, and continued use.

While the machine is designed for use with standard width of paper roll, of say a final net 40 width after removal of the edges of eighteen inches, it will be understood that it may, of course, be made in any suitable size as to width or other dimensions. Also that it may be changed or varied by the skilled mechanic 45 in different features of detail construction, but that all such changes are to be understood as within the scope of the following claims.

What I claim is:

1. A wall paper machine consisting of a 50 supporting frame provided with a roll supporting bracket, a plurality of transverse supporting rollers, a strip supporting platform between said rollers, and an open bottom paste reservoir located immediately above 55 said platform having front and rear lower edges located immediately above the rollers.

2. A wall paper machine consisting of a 60 supporting frame provided with a roll supporting bracket, a plurality of transverse supporting rollers, a strip supporting platform between said rollers, and an open bottom paste reservoir located immediately above 65 said platform and provided with sealing edges located immediately above the rollers adapted to make close contact with a

strip of paper drawn from a paper roll between the rollers and said edges and over the platform.

3. A wall paper pasting machine having a transverse supporting platform and upwardly extending end plates provided with offset holding sockets and a holding latch, and a removable open bottom paste reservoir 70 detachably mounted between the end plates having enclosing side and end walls adapted to 75 bear by their lower edge portions against a strip of paper as it is drawn over the platform, the end walls having lugs for engagement with said sockets and latch.

4. A wall paper pasting machine having a transverse supporting platform and upwardly extending end plates provided with offset holding sockets and a holding latch, and an open bottom paste reservoir mounted 80 between the end plates having enclosing side 85 and end walls adapted to bear by their lower edge portions against a strip of paper as it is drawn over the platform, one of said walls sloping downwardly and forwardly in the direction of movement of the paper strip, the end walls having lugs for engagement with 90 said sockets and latch.

5. In a wall paper machine, the combination with a supporting base, of main sheet metal end plates provided with receiving 95 slots, a transverse paper supporting platform between the end plates, a plurality of transverse paper supporting rollers, and a superimposed open bottom reservoir above the platform having holding devices for mounting 100 the reservoir in said slots.

6. In a wall paper machine, the combination with a supporting base, of a main sheet metal end plates provided with receiving 105 slots, a transverse paper supporting platform between the end plates, a plurality of transverse paper supporting rollers, and a superimposed open bottom reservoir above the platform having holding lugs and locking 110 devices for mounting the reservoir in the 115 slotted end plates and provided with a resilient lower wiping edge.

7. In a wall paper machine, the combination with a supporting base, of main sheet metal end plates provided with receiving 115 slots, a transverse paper supporting platform between the end plates, a plurality of transverse paper supporting rollers, and a superimposed open bottom reservoir above the platform having end walls mounted in the slotted end plates and provided with lower 120 resilient sealing edges and a forwardly extending sloping front wall.

8. The combination with a receiving table, of a pasting machine having a plurality of supporting rollers and platforms on the same general level with the surface of the table, and provided with a removable open bottom 125 paste reservoir for application of paste to the surface of the paper as it is drawn through

the machine over said rollers and platforms to said table, said reservoir having a resilient forwardly extending wiping edge adapted to wipe the paper as it passes from underneath the reservoir.

9. The combination with a receiving table, of a pasting machine comprising a supporting base having a transverse supporting platform and adjacent transverse rollers, a paper roll support beyond the platform adapting a strip to be drawn therefrom over the platform and rollers towards the receiving table, and a superimposed open bottom paste reservoir mounted above the platform and having downwardly extending walls in edge engagement against the platform and rolls.
10. The combination with a receiving table, of a pasting machine comprising a supporting base having a transverse supporting platform and adjacent transverse rollers, a paper roll support beyond the platform adapting a strip to be drawn therefrom over the platform and rollers towards the receiving table, and a superimposed open bottom paste reservoir mounted above the platform and having downwardly extending walls in edge engagement against the platform and rolls.
11. An open top and bottom paste reservoir

consisting of end walls having resilient bearing edges, a rear wall, and a front wall having two downwardly and forwardly extending inclined resilient wiping edges with an intervening space.

36

12. An open top and bottom paste reservoir consisting of end walls having resilient bearing edges, a rear wall, and a front wall having two downwardly and forwardly extending independently adjustable resilient wiping edges with an intervening space.

40

13. In a paper pasting machine, an open top and bottom reservoir having removable holding clamps for securing a paper strip around the upper edges of the reservoir.

45

14. In a paper pasting machine, an open top and bottom reservoir having inwardly inclined sides, and removable holding clamps having inwardly inclined terminals for engagement therewith.

50

15. In a paper pasting machine, an open top and bottom reservoir having inwardly inclined sides, and removable holding clamps consisting of pivotally connected sides provided with inwardly inclined terminals for engagement therewith.

55

In testimony whereof I hereunto affix my signature.

EUGENE C. F. ERNST.
